UNITED STATES PATENT OFFICE.

HERMANN BLEISTREU, OF PHILADELPHIA, PENNSYLVANIA, ASSIGNEE TO THE BALDWIN LOCOMOTIVE WORKS, OF PHILADELPHIA, PENNSYLVANIA, A CORPORATION OF PENNSYLVANIA.

POWDERED-FUEL BURNER.

Application filed April 28, 1920. Serial No. 377,781.

To all whom it may concern:

Be it known that I, HERMANN BLEISTREU, a citizen of Germany, residing at Philadelphia, Pennsylvania, have invented certain improvements in Powdered-Fuel Burners, of which the following is a specification.

My invention relates to certain improvements in powdered fuel burners especially adapted for use in the fire box of locomotives and boilers of the locomotive type. It will be understood that the invention can be used in connection with marine, or stationary, boilers, or in heating furnaces in general.

One object of my invention is to provide an apparatus for burning powdered coal, which can be used, particularly in locomotive boilers, without burning out the fire brick or injuring the tubes of the boiler to any appreciable extent.

A further object of the invention is to use a series of burners and to arrange the burners so that the fuel will be projected towards the center of the combustion chamber. The fuel from the several nozzles is so projected that it will be properly consumed, air being admitted from above and below the fuel in order to keep the fuel in suspension, the floor and roof of the combustion chamber being protected.

In the accompanying drawings:

Fig. 1 is a longitudinal sectional view through the fire-box of a locomotive boiler to illustrate my invention;

Fig. 2 is a sectional plan view on the line 2—2, Fig. 1;

Fig. 3 is a transverse sectional view on the line 3—3, Fig. 1;

Fig. 4 is a longitudinal sectional view of a modification of the invention, the section being through the fire box of a locomotive boiler, showing the means for heating the air prior to its entering the combustion chamber;

Fig. 5 is a sectional view on the line 5—5, Fig. 4;

Figs. 6 and 7 are sectional plan views taken on the lines 6—6 and 7—7, Fig. 4 respectively.

Referring in the first instance to Figs. 1, 2 and 3, 1 is the frame of the locomotive. 2 is the rear end of the locomotive boiler enclosing the ordinary fire box 3. 4 is a floor of fire brick, in the present instance, extend-

ing the full length of the fire box. 5 is the rear wall of fire brick and forms the rear wall of the combustion chamber 6. 7 designates the side walls of the combustion chamber, also of fire brick and tapered from the rear end towards the front, as clearly shown in Fig. 2. 8 is the roof of the combustion chamber, preferably arched, as shown in the cross sectional view, Fig. 3. This combustion chamber opens into the fire box 3. At the opposite end of the fire box 3 is an inclined wall 9 of fire brick and the distance between this wall and the end of the primary combustion chamber may be varied as circumstances allow. At each side of the fire box from the combustion chamber to the wall 9 is a series of air inlets 10 and the air passing through these inlets may be controlled by any suitable apparatus.

At each side of the combustion chamber is an air chamber 11, each receiving air through a pipe 12 having dampers 13 operated by a rod 14 projecting above the platform 15. Each air chamber communicates with the combustion chamber through a series of slots 16 near the roof of the combustion chamber and a series of slots 17 near the floor.

18 designates a series of nozzles connected to pipes 19, which, in turn, are connected to a manifold 20. These nozzles are flat and in the present instance are made of round pipe flattened so that the nozzles will be of the proper length to allow the pulverized fuel to be projected into the furnace. The manifolds 20 are connected by pipes 21 to a union 22 having three branches 23 to which are coupled flexible tubes of the fuel feeding apparatus mounted on the tender.

In the present instance, I have shown three nozzles on each side of the combustion chamber. The nozzles on one side face the nozzles on the opposite side. Above and below each nozzle are the passages for air. By this arrangement the powdered fuel, as it is projected under pressure into the combustion chamber from the several pairs of opposed nozzles is thoroughly mixed and the air above and below the nozzles tends to hold the fuel in suspension and at the same time protects the fire brick from the intense heat.

Furthermore, the direction of the flame of the burning fuel is deflected at right angles and, consequently, its travel longitudinally

in the combustion chamber and the fire box is considerably less than the travel of the fuel from the ordinary burner, which is located at the rear of the fire box. Therefore, 5 this burner, while supplying the desired degree of heat, does not break down the fire brick, particularly at the wall 9 and does not injure the tubes to such an extent as the burners heretofore used, so that the apparatus 10 is especially adapted for use in locomotive boilers where the space in the fire box is comparatively limited.

In some instances, I may provide a heating chamber for heating the air prior to its 15 entering the combustion chamber. In Figs. 4, 5, 6 and 7 I have shown such a device. 33 is a casing having partitions or deflectors 34 so as to cause the air to travel in a circuitous path from an inlet conduit 35 to 20 the passages leading to the slots or ports 16 and 17. This casing is enclosed in fire brick, as shown in the drawings. In this instance, I have shown a fire brick deflector 36 located 25 in the fire box of the locomotive so that the products of combustion, after passing from the combustion chamber, circulate around this deflector before entering the tubes of the boiler.

I claim:—

30 1. The combination in a powdered fuel burning apparatus, for locomotives, of a fire box; a combustion chamber at one end of the fire box and communicating therewith; a series of fuel nozzles at each side 35 of the combustion chamber communicating therewith; means for feeding powdered fuel through the nozzles and into the chamber; means for supplying air to said chamber; and a wall in the fire box opposite the combustion chamber, said fire box having an inlet passage between the combustion chamber and the wall.

2. The combination of a combustion chamber open at one end and closed at top 45 and bottom and at the rear end and flaring towards the open end; a series of nozzles at each side of the chamber and communicating therewith; means for feeding powdered fuel through the nozzles and into the combustion chamber; air ports opening into the chamber at each side thereof; and means for supplying air to said ports so that the powdered fuel will be held in suspension, the

flame of the burning fuel passing out of the open end of said chamber. 55

3. The combination of a combustion chamber; a series of fuel nozzles at each side of the chamber and communicating therewith; means for supplying powdered fuel to said nozzles; a series of air ports communicating 60 with the combustion chamber below the fuel nozzles; and a series of air ports also communicating with the chambers above the fuel nozzles, the combustion chamber being closed at top and bottom and at the rear end 65 and open at the opposite end so that the fuel projected from the nozzles will commingle, the flame of the burning fuel passing out of the open end of the chamber.

4. The combination in means for burning powdered fuel, of a casing forming a combustion chamber open at one end only and flaring towards said end; a series of fuel nozzles at each side of the chamber and communicating therewith; air ports communicating 70 with the chamber above and below the fuel nozzles; air chambers with which the air ports communicate; means for supplying the chambers with air; and means for feeding powdered fuel to the nozzles. 75

5. The combination of a locomotive fire box having a fire brick wall in the front end thereof; a combustion chamber at the rear portion of the fire box and open in line with the fire brick wall; a series of fuel nozzles 80 communicating with the combustion chamber at each side thereof; and means for supplying air to the chamber above and below the nozzles; the fuel projected from the nozzles commingling and the flame of the burning fuel passing out of the open end of the chamber towards the fire brick wall. 85

6. The combination of a locomotive boiler having a fire box; a combustion chamber located in one end of the fire box, said chamber being closed with the exception of, the front end; a series of nozzles located at each side of the said chamber and communicating therewith; means for feeding powdered fuel to the nozzles; a series of air ports opening 90 into the chamber at each side thereof; and heating chambers located within the fire box of the boiler and communicating with the air ports. 100

HERMANN BLEIR TREU.
